UNITED STATES PATENT OFFICE.

ROBERT H. SCROGGINS, OF FAIRFAX, VIRGINIA.

STREET-SWEEPING MACHINE.

1,060,506.

Specification of Letters Patent. Patented Apr. 29, 1913.

Application filed August 6, 1910. Serial No. 575,869.

To all whom it may concern:

Be it known that I, ROBERT H. SCROGGINS, residing at Fairfax, in the county of Fairfax and State of Virginia, have invented a new and Improved Street-Sweeping Machine, of which the following is a specification.

This invention relates to improvements in that class of motor driven street sweeping machines in which the sweepings are conveyed, by suitable elevating devices, into a discharge that empties into a receiver carried by or movable with the sweeping machine or carriage.

My invention primarily has for its object to provide an improved construction of machine of the general type stated, in which the coöperating parts are so designed and combined, whereby a compact arrangement of the mechanism is provided for, which can be economically constructed and in which the controlling devices for the several independently actuated means can be readily manipulated by the driver and in such a manner that he can take care of the actuating mechanism without interfering with a quick and positive action of throwing the motive power and in consequence all the working parts out of gear, and for lifting either the main or supplemental rotary brushes out of contact with the surface while under rotary action.

With other objects in view that will hereinafter appear, my invention consists in the improved street sweeping machine, embodying the peculiar construction and novel arrangement of parts, all of which will be hereinafter fully explained, specifically pointed out in the appended claims and illustrated in the accompanying drawings, in which:

Figure 1, is a side elevation of my street sweeping machine, the brushes being at their lower or sweeping position. Fig. 2, is a plan view of the machine, parts being broken away and shown in section to the better illustrate the correlation thereof. Fig. 3, is a vertical, longitudinal section of the same, taken practically on the line 3-3 on Fig. 2. Fig. 4, is a detail section of the cross conveyer or auger hereinafter specifically referred to. Fig. 5, is an end elevation. Fig. 6, is a detail view of a modified form of elevating lifting blade or bucket.

In the practical application of my invention, the power and actuating devices are

mounted on a suitably constructed vehicle or wagon framing, that includes the front and hind sets of wheels 1-2 and the bed or platform 3, from which extend standards 4-4 to support a decking or covering 4^a mounted over the motor mechanism and the operator's seat.

5 designates a motor of any approved construction, mounted on the forward end of the platform and which is covered from the dust or dirt as it is being swept up, by a sheet metal housing 50, and to assist in driving the dust forwardly and to protect the operator therefrom, the motor is coupled with and drives a fan 51 that operates just inside of the slatted front wall 52 of the housing as is clearly shown in Fig. 3, by reference to which it will be also observed the motor has its fly or power wheel 54 formed with a cone clutch rim 54^a for coacting with a cone clutch disk 60 slidable and keyed on the driven or power transmission shaft 6. The clutch disk 60 is controlled by a lever 7 pivotally mounted adjacent the operator's seat 8, the said-lever having connection with the annularly grooved clutch collar 54^b through the link 71 and the straddle head 72 that seats in the groove of the collar 54^b, it being obvious, see Fig. 3, that by adjusting the lever 7 to the position shown, the shaft 6 will be in gear with and driven by the motor and thus transmit the power for actuating all of the active or working parts of the sweeper, but when shifted back in the direction of arrow α the motor and the driven shaft will be disconnected.

9 designates the main rotary sweeping brush, the shaft of which is journaled in the forwardly and downwardly extended ends 10 of a pair of oppositely disposed and parallel side arms 11 that are tiltably supported on a cross shaft 12 (presently again referred to) and the rear ends of 100 which are longitudinally slotted as at 11^a-11^b to receive the studs 13^a on the cranks 13 fixedly connected to a rock shaft 14 that extends transversely of and is suitably mounted on the platform, it having a 105 fixed connection with a lever 15 that extends upwardly for being conveniently handled by the operator, whereby, by a proper shifting of the said lever, the tilttable side arms with the rotary brush mounted thereon 110 can be readily raised or lowered. At this point it should be stated, a supplemental

and smaller rotary brush for working in corners or close to the curbs is included in my complete construction of machine, and the said smaller brush is mounted so it can be raised or lowered as desired, and for such purpose another lever 16 is disposed adjacent the operator's seat that is linked with a crank member 17 sleeved upon the rock shaft 14, see Figs. 1 and 3 and that joins 10 through the link rod 17^a with a bell crank lever 18 on the forward end of the platform and which, through the link rod 18^a joins with the supporting yoke frame of the smaller rotary brush.

15 The smaller or supplemental brush, in my complete machine structure, is located at one or both edges of the front end of the machine, and is diagonally positioned and forwardly projected with respect to the said 20 end, as best shown in Fig. 2, such arrangement of the supplemental brush making it possible to direct the same to and project the same into corners and such places where it would be impossible to point the supplemental brush were it positioned in front of or at the side of the main brush mechanism in planes parallel therewith. The smaller brush 19 has its journals 19^a mounted in the pendent ends of a yoke frame 20 that 25 includes a rearwardly extended horizontal bifurcated portion 20^a, see Fig. 2, in which the adjacent end of the lower shaft 21 for the elevator presently again referred to, is projected and located in the bifurcated portion 20^a is a bevel drive gear 22 mounted 30 on the shaft 21 that meshes with a similar gear 23 journaled on a stub 23^a projected from the yoke frame 20 to impart rapid motion to the said brush as the main brush is 35 in action.

Referring again to Fig. 3 it will be seen that the main brush is located in a housing 26 the side walls of which have segment slots 26^a to permit the rise and fall of the main 40 brush, and each journal end of the main brush carries a chain gear 27 around which take the endless chain belts 28 that also pass over drive chain gears 29-29 on a cross shaft 12 mounted in journal boxes on the 45 under side of side beams of the platform, the said shaft 12 receiving motion through a chain belt 31 that engages a chain wheel 32 on the shaft 12 and a like wheel 33 that is loosely mounted on the motor driven shaft 50 6 and having a clutch face 34 for coating with a sliding clutch 35 on the said driven shaft, with which connects a bell crank 36 controlled by a lever 37 adjacent the driver's seat, it being apparent the latter clutch 55 mechanism is utilized for controlling the starting and stopping of the rotary sweeper and the elevator mechanism that coacts therewith.

Coöoperating with the main driven shaft 60 is a second driving shaft 34' that meshes

with the main shaft through the gears 35'-36' and the said shaft 34' carries chain gears 34^a around which take driving chain belts 37'-37' that pass around large chain wheels on the axles of both of the hind 70 wheels of the truck, as is clearly shown in Figs. 1 and 3.

For stopping and starting the motor engine, I connect the motor controlling valve rod 38 with a bell crank 39 mounted on a bearing pendent from the truck frame and connected through a link 39^a with a lever 40 adjacent the driver's seat.

At the lower or take-up end of the main 80 sweeper roll is pivotally suspended a dust or dirt pan 41, the opposite ends 41^a of which straddle the corresponding ends of the brush and serve to positively collect the dirt swept up and to direct it in an upwardly and forwardly direction. The pan 41 is pivotally 85 hung as at 41^b to the lower inner side of the housing for the elevator and to provide for holding the receiving end close up or slightly away from the lifting side of the brush, the lower end of the pan is adjustably 90 suspended by the flexible hangers or chains 42-42, see Fig. 1.

The main brush, except at its take-up end, is incased by the sheet metal housing 26, the rear part of which is extended down 95 across the back side of the main rotary brush, see Fig. 3.

The elevator 82 is of the usual endless belt slat kind has its lower end passed over a belt wheel 82^a on the shaft that drives the 100 supplemental brush, its upper end taking over a belt pulley 83 on a shaft 84 that has a pulley 85 belted to a smaller pulley 86 on an auxiliary shaft 86^a that carries a transversely disposed auger or worm 105 conveyer 87 located in the bottom of a collecting trough 87^a into which the sweepings are dropped by the elevator belt as is clearly shown in Fig. 3 of the drawings.

88 designates a supplemental conveyer 110 that is disposed lengthwise of the machine and carries the collections from the front end to the rear end of the machine to be discharged into the receiving sacks, as shown, or if desired, into a separate collecting cart or wagon. The conveyer 88 has its receiving end located just under the discharge end of the auger trough and its conveyer belt 89 is driven by the chain pulley 90 on one end of the shaft 92 on which the lower belt pulley 93 of the conveyer 88 is mounted, and with which engages a drive chain 94 that passes over a chain wheel 95 on the auger shaft and over a drive wheel 96 mounted on a shaft 12 that extends across 120 the machine and is journaled in bearings 98 pendent from the platform. The longitudinally extended conveyer 88 inclines slightly upward from the receiving to the discharging end to cause a more perfect 130

dragging of the collections toward the delivery end of the said conveyer 88 and the said conveyer terminates in a pendent throat 88^a which, in practice, may be of such length and so positioned that it can be readily sustained over a collecting wagon or cart, not shown, or utilized for sustaining cut-off mechanism for bagging into which the collections can be discharged.

10 In Fig. 2 it will be noticed I have shown two oppositely disposed bag hangers, each of which consists of a pendent arm 101, one of which is pivotally hung on each side of the throat piece and has a crank 102 at the 15 upper end connected through pendent rods 103 with a treadle lever 104 mounted on a sub-platform 105 pendent from the rear end of the main platform. At the lower end each arm 101 has a substantially semi-circular rim 105^a formed with hanger pins 106 and the treadle connects with the said arms in such manner that the mouth of the bag or receiver X can be readily slipped up over the two rims 25 105 and when thus fitted, by pressing down on the foot lever the rims 105 are opened out to cause their rims to spread and the mouth of the bag to securely hold it in place, a hand lever 106^a being used in connection 30 with a curved cut-off 107 for closing the discharge from the bag receiver while taking off or putting on the bags or holders.

From the foregoing, taken in connection 35 with the accompanying drawings, it is believed the complete structure, the manner in which my machine operates and the advantages thereof will be readily apparent to those skilled in the art to which my invention relates.

40 It will be understood that slight changes in the details of construction shown, and modifications thereof may be made without departing from my invention as expressed in the appended claims. For example, instead of utilizing the conventional type of lift slats on the main elevator, bucket-like slats or lift portions arranged as shown in Fig. 5 may be used and this form is especially advantageous for use on streets where 45 the soil or sweepings are mucky or wet.

50 The main points of advantage of my invention are the arrangement of the controlling lever mechanism so the driver can easily

adjust and control the entire operation of adjusting the parts or setting them in and 55 out of operation. Again, by arranging the elevator at the front to extend the full width of the machine and housing the elevator as shown, the bulk of the dust from the sweepings is carried off with the take-off or longitudinal conveyer while the blast fan arrangement tends to positively drive forwardly what other dust comes up from the brushes and thus protect the driver. Placing the motor mechanism as shown, balances the machine and permits of an inexpensive and easily controlled arrangement of power transmission gearing being utilized.

While but one supplemental brush is 70 shown and described, it is obvious that a supplemental brush may be used for each corner of the sweeping end of the machine.

A water tank, indicated by α on the drawings, is mounted on the truck or motor 75 wagon and extends lengthwise thereof, with which, in practice, sprinkling means of any approved type may be connected.

Having thus described my invention, what I claim is:

1. In a street sweeping machine, a main dirt gathering and elevating mechanism, the said mechanism including a lower elevator shaft, and means for operating the same; a supplemental dirt gathering means 85 including a supporting device pivoted on the said elevator shaft, and power transmission connecting said supplemental gathering means and the said lower shaft.

2. In a street sweeping machine, a main 90 dirt gathering and elevating mechanism, the said mechanism including a lower elevator shaft, and means for operating the same; a supplemental dirt gathering means including a supporting device pivoted on 95 the said elevator shaft, and power transmission connecting said supplemental gathering means and the said lower shaft, and means for elevating the said support and the supplemental gathering device carried 100 thereby without disconnecting the power transmission connections.

ROBERT H. SCROGGINS.
